UNITED STATES PATENT OFFICE.

WILLIAM JOHN BROWN AND JOHN O. THORN, OF TORONTO, ONTARIO,
CANADA.

SHEET-METAL SHINGLE.

SPECIFICATION forming part of Letters Patent No. 409,387, dated August 20, 1889.

Application filed April 8, 1889. Serial No. 306,298. (No model.)

To all whom it may concern:

Be it known that we, WILLIAM JOHN BROWN, mechanic, and JOHN ONIONS THORN, book-keeper, both of the city of Toronto, in the 5 county of York, in the Province of Ontario, Canada, have jointly invented a certain new and Improved Sheet-Metal Shingle, of which the following is a specification.

The object of the invention is to design a 10 sheet-metal shingle which will be easily secured to the roof with protected joints, and a series of which is specially adapted to form a valley, and it consists, essentially, of a series of 15 metal shingles bent angularly to form a valley, the bottom edge of each shingle overlapping the top edge of the shingle below it, and the sides of each shingle being crimped to form an angular overhanging wall on each side of the valley, and on the outside of each wall a 20 gutter with a nailing-edge extending beyond it, the inner wall of the said gutter being bent inwardly to form a recess into which the straight edge of the adjoining shingle may fit to form a cap for the gutter and the nailing- 25 edge, substantially as hereinafter more particularly explained.

Figure 1 is a view of a roof showing the application of our improved shingle and valley. Fig. 2 is a sectional plan through *x y*. Fig. 30 3 is an enlarged edge view of the shingle, having a nailing-edge on one side only.

As our shingle is specially invented and adapted for the formation of a valley with a water-tight joint, we shall first explain its application for this purpose and will draw attention to Fig. 1. In this figure it will be noticed that the shingles *A* are bent angularly to form the valley, and we may mention here that the bottom of each shingle overlaps the 35 top edge of the shingle below it, so as to prevent any water passing through the joint. It will be observed that the sides of the shingles *A* are crimped, the angular overhanging wall *a* being formed on each side of the valley, so as 40 to prevent the water in the valley from flushing over its sides. From this angularly-

formed wall the surface of the shingle extends a short distance, and is then bent downwardly and inwardly to form a recess *b*, and is then bent back to form a gutter, the outer edge of 50 which extends at substantially right angles to the bottom of the gutter to a point about level with the flat surface of the shingle. The edge of the shingle is then bent down to form a nailing-edge *d*. The recess *b* is intended to 55 receive the straight edge of the adjoining shingle, which forms a cap for the gutter and for the nailing-edge.

A shingle shaped as described not only forms a very effective covering, the sections 60 of which may be readily secured and hermetically connected, but they are specially adapted to form a superior valley.

What we claim as our invention is—

1. A metal shingle having one side crimped 65 to form a gutter with a nailing-edge extending beyond it, the inner wall of the said gutter being bent inwardly to form a recess, into which the straight edge of the adjoining shingle may fit to form a cap for the gutter 70 and for the nailing-edge, and an angular overhanging wall, substantially as and for the purpose specified.

2. A series of metal shingles bent angularly 75 to form a valley, the bottom of each shingle overlapping the top edge of the shingle below it, and the sides of each shingle being crimped 80 to form an angular overhanging wall on each side of the valley, and on the outside of each wall a gutter with a nailing-edge extending 85 beyond it, the inner wall of the said gutter being bent inwardly to form a recess, into which the straight edge of the adjoining shingle may fit to form a cap for the gutter and for the nailing-edge, substantially as and for the purpose specified.

Toronto, March 25, 1889.

WILLIAM JOHN BROWN.
JOHN O. THORN.

In presence of—
CHARLES C. BALDWIN,
W. G. McMILLAN.
